(57) **CLAIM**

The ornamental design for a security camera, as shown and described.

DESCRIPTION

FIG. 1 is a front perspective view of a security camera according to the present design;

FIG. 2 is a front elevational view of the security camera of FIG. 1;

FIG. 3 is a rear elevational view of the security camera of FIG. 1;

FIG. 4 is a right-side elevational view of the security camera of FIG. 1;

FIG. 5 is a left-side elevational view of the security camera of FIG. 1;

FIG. 6 is a top plan view of the security camera of FIG. 1; and,

FIG. 7 is a bottom plan view of the security camera of FIG. 1.

The broken lines depict portions of a security camera in which the design is embodied that form no part of the claimed design.
